OIL BATH AIR CLEANER CONSTRUCTION

Lyle J. Hamman, Eaton Rapids, Mich., assignor
to Eaton Stamping Company, Eaton Rapids,
Mich., a corporation of Michigan

Application May 16, 1949, Serial No. 93,459

10 Claims. (Cl. 183—15)

1

This invention relates to air cleaners such as are employed to clean the air supply to internal combustion engines, compressors and the like and more particularly to air cleaners of the liquid bath type.

In general, air cleaners of the above type comprise a cup-like casing for holding a body of oil or other liquid to constitute the liquid bath. This liquid bath is employed in association with a filter unit supported upon the casing above the liquid level, the construction and arrangement being such that the air to be cleaned is constrained to come into contact with the liquid in its passage through the interior of the casing. This liquid serves not only to clean the filter but also to collect solid impurities in the air by contact of the air with the liquid. It is an essential requirement of these air cleaners that the liquid should be maintained at a predetermined high level or should not fall below a predetermined low level and further, that these levels should be correctly located relatively to the bottom of the filter unit when in position upon the casing. While in the known air cleaner constructions provision is made for securing the filter unit upon the casing, these constructions do not permit observance of whether the filter unit is correctly located with regard to the predetermined liquid levels, becomes a matter of chance, therefore, whether the filter unit is correctly positioned within the casing. On the other hand it is well recognized that the introduction of solid impurities with the air supply to internal combustion engines gives rise to serious trouble, and that if the air cleaners employed are to be of any use at all, it is essential that the filter unit and the liquid bath should be correctly located, or maintained, relatively to one another.

It, therefore, becomes an object of the invention, in an air-cleaner of the above described type, to provide an improved construction of the casing, which permits the filter unit to be supported and located at a proper and definite position relatively to the predetermined high and low liquid levels and which, in particular, permits this location to be readily discerned from outside the container.

These and other objects and advantages of the invention will appear clear from a consideration of the following description with reference to the accompanying drawings and from the annexed claims.

In the drawings,

Fig. I is a vertical section through an air

2

cleaner construction in accordance with the invention.

Fig. II is a vertical section of the one-piece body structure provided by the invention and made from a light transmitting plastic material, and

Fig. III is a plan view of Fig. II.

Referring to the drawings, 10 indicates a cup-like liquid supporting body, 12 a bottom duct part by which the filter apparatus as a whole is capable of being mounted in operative association with respect to the air intake of an internal combustion engine, 14 a top cover part or lid cover and 16 the air filter unit.

15 The body 10 is conveniently molded in one piece from light transmitting plastic material to provide a central axial air flow tube 18 open at its opposite ends and connected at its lower portion with the adjacent interior surface of the body 10 by integral radial webs or partitions 20 which define a series of separate liquid retaining pockets 22 at the bottom of the body part. This body part is intended to hold a body of oil or suitable liquid, which is filled to a high level in the body and has a permissible low level therein, both such levels being indicated in Fig. I.

20 The central air flow tube 18 serves for the telescopic mounting of the filter unit 16, formed by a cylindrical outer shell 24 having an annular base 26 with a circular series of perforations 28 and an annular cover plate 30 with a circular series of perforations 32, the annular space defined between the plates being filled with a suitable air filtering body 34.

25 The bottom plate 26 is formed around its inner periphery with an upturned flange 36 while the upper plate (which is shown separately formed and secured to the shell 24 by an outer upturned flange 38), is formed around its inner periphery with a down-turned flange 40 axially aligned with the flange 36 and combining with the latter to provide a guide for the sliding engagement of the filter unit upon the tube 18.

30 The shell 24 defines an annular down-flow chamber 42 within the body 10, having an annular entrance 44 defined between the outwardly flared skirt 46 at the bottom of the lid 14 and the upper open end of the body 10, the general direction of the air flow being indicated by the arrows 45 in Fig. I.

35 As will be observed from consideration of Figs. I and II, the upper edges of the radial webs 20 are each formed with recess 48, the bottom of which extends below the permissible low liquid level but the top of which recess, at the outer

side thereof, terminates in a ledge 48 disposed at substantially the high liquid level and in immediate proximity to the shell 24, which is located on this ledge as indicated at 50 in Fig. I.

The lid 14, on the other hand, has its flared bottom 44 joined with the top of the lid by an annular ledge 52 which is positioned in immediate proximity to the upper end of the shell 24.

The lid 14, the top of which is shown formed with radial strengthening ribs 54, has a central opening 56 through which the upper screw-threaded end 58 of a rod 60 extends and receives a tightening nut 62, this rod passing axially through the center of the tube 18 and being retained against the outside of the duct 12 by the engagement of the head 64 at the lower end of the rod. The construction has the advantage that when the nut 62 is tightened, the pressure is applied through the annular lid ledge 52 axially upon the shell 16 and in immediate opposition to the ledge 48, whereby tube 18 is relieved of all strain and the filter unit as a whole is firmly and positively located in its desired operating position.

The radial webs 20 have the advantage that the liquid space at the bottom of the body 10 is subdivided into a series of separate pockets in which the liquid is constrained against "slopping-over" under conditions of tilt, i. e. when the filter apparatus as a whole is subjected to tilting in use. Further, by locating the bottoms of the recesses 46 in proximity to, or below, the low liquid level it is ensured that the combined liquid levels, merge into a common level in the normal upright position of the filter apparatus. The bottoms of these recesses, in effect, constitute inter-communicating outlets between the separate liquid pockets 22, and might well take the form of holes in the webs, except that these are not so convenient to form, bearing in mind that the body is to be molded in one piece from a light transmitting plastic material to yield the advantage that it is possible to see into the interior of the body. Thereby, the important result is obtained that a person assembling the filter unit upon the casing is able to see that the bottom of the filter is firmly seated upon the ledges 48 and thus leaves the filter unit correctly positioned relatively to the predetermined liquid levels.

Having thus described my invention in practical application but without limitation to the precise details of instruction thereof involved, what I claim as novel and wish to secure by Letters Patent is as follows:

1. In a down-flow air filter, a molded plastic hollow casing structure open at the top and having an integral air outlet opening at its lower end, supporting structure within said body structure, integral therewith, and defining an annular ledge surface, an air-flow tube upstanding around the opening, a filter unit mounted within said casing around said tube, said filter unit including a casing defining a down-flow air space between itself and the interior of said body structure and constraining the air flow to pass through the filter unit in its passage to said outlet opening, said casing having seating engagement at its one end with said annular ledge surface, and a lid closure for said open top end of the casing structure and including a companion ledge surface to said annular ledge surface, said closure defining an annular air inflow opening into said down-flow air space and having its ledge surface in endwise pressure applying relationship to said filter unit casing,

whereby to hold the latter located against the ledge surface on said supporting structure.

2. The invention as defined in claim 1, said hollow casing structure having a central tubular portion defining a down-flow air passage, said filter unit being of annular formation and guided about said tubular portion, and a series of webs or partitions in the bottom portion of said casing structure and integral therewith defining separate liquid retaining pockets beneath said filter unit.

15 3. A body structure for an air cleaner, said structure being adapted to support a body of liquid in its bottom portion, a down-flow air tube extending upwardly from the bottom of said body structure, and substantially radial webs in the lower portion of said structure defining separate retaining pockets for said liquid, said entire body structure being formed in one piece from a light 20 transmitting material which enables the interior of the structure, and hence the liquid, to be viewed from the outside.

25 4. A body structure for an air cleaner of the down-flow type, said structure having a cup portion in its lower part adapted to support a body of liquid, and a down-flow air tube extending upwardly from the bottom of the cup portion of said body structure, said entire body structure being formed in one piece from a transparent material 30 which enables the interior of the structure to be viewed from the outside.

35 5. A unitary body structure for an air cleaner formed in one piece from a transparent material which enables the interior of the structure to be viewed from the outside, said body structure having a cup portion in its lower part adapted to receive and hold a body of liquid and being provided with a down-flow air tube extending upwardly from the bottom of said cup portion, and 40 said body structure having spaced apart webs on the inner wall of the cup portion extending substantially radially inwardly toward the air tube.

45 6. A unitary body structure for an air cleaner, said structure having a cup portion in the lower part thereof and being provided with a down-flow air tube extending upwardly substantially centrally from the bottom of the cup portion, said body structure being of transparent material through which the interior can be viewed 50 and being provided with a liquid level marking thereon, and said body structure being provided with a series of spaced upright webs on the inner wall of the cup portion extending inwardly from the wall of the cup and having supporting ledge portions substantially at the upper liquid level.

55 7. A unitary body structure for an air cleaner consisting of an upright substantially cylindrical transparent portion having a liquid containing cup portion in its lower part adapted to hold a body of liquid and provided with a down-flow air tube extending substantially upwardly from the bottom of the cup portion, said body structure on the cup portion thereof having a liquid level marking visible from the outside and being provided inwardly with a spaced apart series of upright webs on the wall of the cup portion extending inwardly from the wall of the cup toward the air flow tube and having supporting ledge portions substantially at the liquid level with the upper portions of the webs above the ledge portions presented as filter unit centering ribs.

70 8. In an air cleaner adapted for use to clean air at the intake of an internal combustion en-

gine and the like, a unitary body structure of molded transparent plastic material which enables the interior of the structure to be viewed from the outside, said body structure having a cup portion in the lower part thereof adapted to receive and hold a body of liquid and being provided with an upstanding annular wall having an open upper end, said body being provided with a liquid level marking on the cup portion and said body structure having an annularly spaced apart series of radially disposed webs on the inner wall of the cup portion and extending upwardly on the annular wall, said webs having supporting ledge portions above the liquid level marking, an air filter unit having an outer shell spaced from the annular wall resting at its lower end on the ledges and thus elevated above the liquid level and said shell and filter unit rising above the open top end of the body, and a cover supported on the upper end of the shell and provided with a flared skirt portion overhanging and spaced above the open upper end of the body.

9. In an air cleaner, a hollow body structure adapted to support a body of oil or other suitable liquid in the bottom thereof, a filter unit, means supporting said filter unit upon said body structure in air flow constraining relation and above said liquid, and a series of webs or partitions in said body extending radially inwardly from the outer wall and subdividing the bottom liquid space therein into a series of separate liquid retaining pockets, said webs or partitions including surfaces locating the bottom of said filter unit at a predetermined level in said body structure corresponding to a required liquid level, said

webs or partitions having recesses in their upper edges with the bottoms of the recesses situated in the vicinity of the permissible low liquid level and the recesses terminating at the top in ledges upon which the bottom of said filter unit is capable of being located and supported.

10. In an air cleaner, the combination of a unitary molded plastic hollow body part having an open upper end and having an air flow tube upstanding in its middle, supporting structure integral with said body part and including a ledge surface, a removable lid closure for the upper end of the body part, a filter unit including an outer shell casing adapted for engagement with said ledge surface, and means extending through the air flow tube adapted to secure said lid closure upon the body part in endwise pressure applying relationship to said shell casing with the casing held engaged against said ledge surface.
